UNITED STATES PATENT OFFICE.

THADDEUS F. BAILY AND FRANK T. COPE, OF ALLIANCE, OHIO, ASSIGNEES TO THE ELECTRIC FURNACE COMPANY, OF ALLIANCE, OHIO, A CORPORATION OF OHIO.

SHEET-FEEDING MACHINE.

1,276,608.

Specification of Letters Patent. Patented Aug. 20, 1918.

Application filed February 14, 1916. Serial No. 78,323.

To all whom it may concern:

Be it known that we, THADDEUS F. BAILY and FRANK T. COPE, citizens of the United States, both residing at Alliance, in the county of Stark and State of Ohio, have invented a new and useful Sheet-Feeding Machine, of which the following is a specification.

This invention relates to sheet feeding machines and has more especial reference to a device adapted to feed sheets from a car or tank preparatory to placing the sheets in a tinning pot.

The object of the present invention is to provide a device adapted to automatically feed sheets singly from a car or tank.

A further object is the provision of a device of this character which will feed the sheets upon a suitable table from which they may be manually removed and to so constrain the device that should the operator leave the machine for a few minutes the machine will be automatically stopped after a certain number of sheets have been fed therefrom.

A still further object is to provide a device of this character which is suspended above the car or tank and automatically moves along the length thereof as the pack of sheets therein is diminished.

With these objects in view the invention consists in the novel construction and arrangement of parts, hereinafter described, illustrated in the accompanying drawings, and particularly pointed out in the appended claim, it being understood that various changes in the form, proportions, size and minor details of construction may be made within the scope of the appended claim, without departing from the spirit or sacrificing any of the advantages of the invention.

In the drawings:

Figure 1 is a longitudinal sectional view through a device constructed in accordance with our invention, showing the same in the act of feeding sheets from a car.

Fig. 2 is a side elevation of the same.

Fig. 3 is a front elevation of the same.

Fig. 4 is a side elevation of one of the side frames.

Fig. 5 is a detail sectional view of the three-way valve which controls the operation of the suction cup.

Fig. 6 is a detail view showing a modified form of the device.

Similar numerals of reference indicate corresponding parts throughout the several figures of the drawings.

Referring more especially to the construction illustrated in the accompanying drawings, the numerals 1—1 indicate tracks supported in any suitable manner and adapted to carry the sheet feeding mechanism, the cars, such as indicated by the numeral 2, being adapted to run beneath said tracks as shown in Fig. 1. The numerals 3—3 indicate side frames upon which the feeding mechanism is carried, the wheels 4 being provided in said side frames by means of which the device may be moved upon the tracks 1. Rolls 5 and 6 are journaled in suitable bearings 7 and 8 respectively which are carried by the side frames 3, the bearings 7 being slidably mounted within slots 9 formed in the side frames, springs 10 being located between said bearings 7 and stationary blocks 11 for the purpose of holding the rolls 5 and 6 together. A gear 12 is mounted upon the shaft 13 of the roll 5 and meshes with a gear 14 mounted upon the shaft 15 of the roll 6, the gear 12 also meshing with an idler 16, said idler meshing with a pinion 17 mounted upon a shaft 18 of the motor 19. The motor 19 is preferably mounted upon a bracket 20 suspended between the side frames as best illustrated in Fig. 3.

A large gear 21 is mounted upon each of the side frames and meshes with a small gear 22 mounted upon the short shaft 13 and upon each of said gears is mounted a roller 23, the pivoted arms 24 resting upon said roller, each of said arms being pivotally mounted at 25 to one of the side frames. The forward extremities of the arms 24 are connected by means of a rod 26. A pair of downwardly depending arms 27 are carried by the rod 26 and at the lower extremity of each of said arms 27 is pivotally connected a suction cup 28, a flexible hose 29 leading from each of said suction cups to a three-way valve 30.

The valve 30 is preferably swung from a flexible hose 31, which leads to a suction pump or some equivalent device and an air inlet 32 is provided within said valve for the purpose hereinafter described. The rotatable plug 33, within the valve casing is pro-

vided with a port 34 adapted to connect the suction line 31 with the suction cup by means of the flexible hose 29 and with a port 35 adapted to connect the air inlet 32 with the suction cup.

A rock arm 36 is fixedly connected to the rotatable valve plug 33 and mounted upon the free extremity of said rock arm is a yoke 37 provided with the upper and lower fingers 38 and 39 respectively adapted to be engaged by the extremity of the adjacent arm 24 as will be later described. Each of the arms 27 is provided with a bracket 40 and between said brackets and the bracket 41 provided upon the rod 26 is interposed a coil-spring 42 for the purpose of holding the suction cup in engagement with the outer face of the forward sheet in the car, the sheets being designated by the letter A. The suction cups are pivotally mounted upon the arms 27 in order to adjust themselves to the angle of the sheets.

A deflector plate 43 is pivotally mounted between the side frames and beneath the rolls 5 and 6 and adapted to guide the upper extremity of the sheet between the rollers. Mounted upon said deflector plate is a pair of arms 44, the lower extremity of which are provided with anti-friction rollers 45 adapted to contact with the face of the outer sheet. A pivoted button 46, or some other suitable locking means, is provided to normally hold the deflector plate and arms against movement, said plate being pivoted in order to allow the arms to be raised sufficiently to clear the top of a car when a new car is moved into position beneath the feeding device.

An inclined table 47 is pivotally mounted between the side frames and beyond the rolls 5 and 6 and adapted to receive the sheets as they are passed through the rollers. The lower extremity of the table is supported upon a plate 48 which is slidably mounted upon the tracks 1, a spring 49 being interposed between the table and said plate. A stop 50 is provided near the lower extremity of the table for the purpose of engaging the lower extremities of the sheets as they are piled upon the table. The plate 48 is provided with a bracket 51 which carries an electrical contact 52 adapted to contact with a contact 53 carried upon the table 47. The wire 54 which leads from the source of electrical supply is connected with the contact 52 and a wire 55 leads from the contact 53 to the motor 19. The other wire 56 returns from the supply line to the motor, thus it will be seen that when the table is in the position shown in Fig. 1 of the drawings the circuit from the source of supply from the motor is closed and the motor will be operated. Should the operator of the device leave the machine for a few moments it would not be desirable to have the device continuing

to operate and for this reason the above mentioned circuit breaking device is provided. After sufficient sheets have been placed upon the table 47 to compress the spring 49 the lower extremity of the table will be moved downwardly thus breaking the circuit between the contacts 52 and 53 and shutting off the motor. For the purpose of moving the feeding device upon the tracks 1 a flexible member 57 is connected to the side frames and passes over a pulley 58, a weight 59 being connected to the extremity thereof.

The cars 2 which contain the sheets A are filled with water above the level of the sheets as shown in Fig. 1. These cars are run beneath the tracks 1-1 upon which the feeding device is carried. The yoke 37 should be tilted backwardly allowing the pivoted arms 24 to be raised, thus raising the arms 27 and the suction mechanism above the level of the car or tank when each new car is placed in position or an emptied car is moved from beneath the feeder, the arms 24 being pivoted at 25 to allow this movement. The latch 46 should be turned to allow the arms 44 to be raised forwardly to clear the top edge of the car as each new car is brought beneath the device and then the arms may be lowered into the position shown in Fig. 1 and the latch tightened. By this construction the arms 44 will bear against the surface of the forward sheet preventing any further movement of the device toward the rear of the car, the weight 59 holding the device in this position upon the tracks. When the device is operated as the arms 24 move downwardly they will contact with the fingers 39 turning the valve 30 into the position shown in Fig. 5, creating a suction within the suction cups 28 and as the arms are raised in the position shown in Fig. 1 the outermost sheet of the pack will be raised by said suction cups, the upper edge of said sheet engaging the deflector plate 43 and being thrown between the rolls 5 and 6 which grasp the sheet and carry the same upwardly depositing the sheet upon the table 47 from whence the sheet may be removed by the operator and placed in the tinning pot or other device. As the arms 24 reach the upper limit of their movement they contact with the fingers 38 turning the valve 30 sufficiently to connect the air inlet 32 with the hose line 29 by means of the port 35, thus allowing air to flow into the suction cups and releasing the sheet from said suction cups as the sheet is grasped by the rolls 5 and 6. The suction cups will thus be released from the sheets until the arms 24 reach their lowermost limit when they will contact with the fingers 39 moving the valve back into position to create a suction within the suction cups causing them to grasp the next sheet and

carry it up to the feed rolls as above described. If it is desired to dry the sheets as they are removed from the car the feed rolls 5 and 6 may be covered with rubber or similar material which will squeeze the moisture from the sheets as they are passed therethrough.

The rollers 45 upon the arms 44 being always held in contact with the outermost sheet of the pack, the device will move above the pack of sheets as said sheets are fed from the car, the weight 59 causing the device to travel so that the feed rollers are always above the outermost sheet of the pack.

In Fig. 6 is shown a slightly modified form of construction in which electro-magnets are used to feed the sheets to the feed rolls instead of the suction cups above described. An electro-magnet 60 is pivotally mounted upon the lower extremity of each of the arms 27 and two wires lead to said magnet, the wire 61 leading from a source of electrical supply and the wire 62 leading from the magnet to the contact 63. A contact 64 is provided upon the arm 66 and adapted to engage the contact 63 as the arm 36 is operated in the usual manner, a wire 65 leading from the contact 64 to the source of the electrical supply. By this construction the circuit to the magnet is closed as the arms 24 descend, energizing the magnets and causing them to take hold of the outermost sheet of the pack and as the arms 24 are raised into the position shown in Fig. 6 they will contact with the fingers 38 breaking the circuits to the magnets thus deenergizing the magnets thus allowing the sheets to be fed to the feed rolls.

The same result as above described might also be obtained by providing an endless conveyer table above the tank adapted to

carry the sheets from the tank to the operator, an adhesive lifting device being 45 provided to lift the sheets from the tank and delivering the same to said conveyer.

Although the drawings and above specification disclose the best mode in which we have contemplated embodying our invention we desire to be not limited to the details of such disclosure, for, in the further practical application of our invention, many changes in form and construction may be made, as circumstances require or experience suggests, without departing from the spirit of the invention, within the scope of the appended claim.

We claim:

In a device of the character described, the combination with a tank containing a pack of vertically disposed sheets of a horizontal track located above said tank, a frame mounted for movement upon said track, an arm carried by said track and extending into the tank, a roller provided upon said arm and arranged to contact with the outermost sheet of the pack, a pair of feed rollers carried in said frame, means for moving said frame to hold said feed rollers above the outermost sheet of the pack at all times, an oscillating arm pivoted upon said frame, means for oscillating said arm, a vertically reciprocating arm pivotally connected to said oscillated arm and adapted to extend into said tank means upon said reciprocating arm for adhesively engaging the face of the outermost sheet of the pack and means for releasing said sheet after the reciprocating arm reaches the upward limit of its movement.

In testimony that we claim the above we have hereunto subscribed our names.

THADDEUS F. BAILY.
FRANK T. COPE.
